UNITED STATES PATENT OFFICE.

HARRY L. REED, OF DORCHESTER, MASSACHUSETTS.

CONTAINER.

1,179,560.

Specification of Letters Patent. Patented Apr. 18, 1916.

Application filed November 6, 1914. Serial No. 870,663.

To all whom it may concern:

Be it known that I, HARRY L. REED, a citizen of the United States, and a resident of Dorchester, county of Suffolk, and Commonwealth of Massachusetts, have invented an Improvement in Containers, of which the following description, in connection with the accompanying drawings, is a specification, like characters on the drawings representing like parts.

This invention relates to a container for serums and the like preferably equipped with means for maintaining the same hermetically closed which may be readily opened to permit the discharge of the contents.

Among other objects the invention is intended to provide a simple and economical construction and more particularly one which will effectually protect the contents from contamination.

The character of the invention may be readily understood by reference to one practicable embodiment shown for illustration in the accompanying drawings, in which:

Figure 1 is a side elevation; Fig. 2 is a longitudinal axial section on the line 2—2 of Fig. 1; and Figs. 3, 4 and 5 are transverse sections on respective lines 3—3, 4—4, and 5—5 of Fig. 2.

The illustrative construction comprises a body 6 the lower end of which is closed by a rubber stopper 7. It is assumed that the contents of the body 6 are to be discharged through appropriate channels in the stopper 7. To suit this purpose the stopper is provided with one or more conduits 8—8 communicating with a common chamber. In this chamber is a valve plug 9 which may be of hard rubber or other appropriate material. In the illustrative form, this valve plug 9 is a hollow cylinder closed at its upper end and snugly fitting an axial bore made in the stopper 7, the valve plug when in place extending across the open ends of the conduits 8—8 where they intersect the axial bore of the stopper. To coöperate with the conduits 8—8, the valve plug 9 is provided with ports 10—10 (see Fig. 4) extending through the cylindrical wall of

the plug 9. When the plug 9 occupies the position shown in Figs. 2 and 4, imperforate portions of the plug stand opposite the lower mouths of the conduits 8—8 and hermetically close the same. When, however, the plug 9 is rotated about its axis through 90°, the ports 10—10 thereby open communication between the respective conduits 8—8 and the interior of the plug 9. Thus the plug 9 serves to illustrate a means by which the lower end of the container may be effectually closed or sealed normally but which may be readily opened when it is desired to discharge the contents of the body 6.

The lower end of the plug 9 is suitably formed to coöperate with the butt-end or hub of a hypodermic needle and preferably, though not essentially, the needle may be made a permanent part of the valve plug 9. For instance, a shank 12 may project from the hub 13 of a needle into the cylindrical interior of the plug 9 which may be secured to the shank 12 in any practicable manner as by a suitable adhesive. In this manner the plug 9 and the needle hub 13 may be secured together so that the ports 10 may be adjusted from one position to another by turning the needle hub. A needle 14 is shown secured to the hub 13.

To provide for locking the valve plug 9 in its two positions in which it respectively closes and opens the conduits 8—8, the stopper 7 or some other part associated therewith, is provided with a locking seat 15 and a second seat 16 disposed at right angles to the first; and the shank 12 is provided with a locking lug 17 adapted to engage the seat 15 when the plug ports 10—10 register with the conduits 8—8, and to engage the seat 16 (see Fig. 5) when the plug is in position to close the conduits 8—8.

Figs. 2, 4 and 5 show the ports in their normal positions closing the discharge outlets of the body 6, the locking lug 17 being then engaged in the seat 16 to hold the valve plug against rotation which might accidentally open the conduits 8—8. When it is desired to discharge the contents of the body 6, the operator may withdraw the plug 9 slightly to a sufficient extent to re-

lease the locking lug 17 from the seat 16, and may then turn the plug 9 through 90° until the locking lug 17 is in position to register with the seat 15. Thereupon the lug 17 may be pressed into the seat 15 so as to bring the ports 10—10 into register with the lower ends of the conduits 8—8. This opens communication from the body 6 into the interior of the plug 9 and permits the serum or other contents of the body to be discharged through the needle 14.

When the needle and its hub or other support is made a permanent part of the valve plug 9 or equivalent closure, it is preferred that the needle be protected from contamination by some such provision as a glass or other cap 18; which may be fitted over a projection 19 on the stopper 7.

Any practicable means may be employed for discharging the contents from a container such as that above described. For instance, the body 6 could be provided with a piston for ejecting the contents. It is preferred, however, to have the upper end 25 of the body 6 closed by a stopper 20 having therein a tubular member 21 internally threaded at its upper end to receive a screw plug 22 conveniently provided with a knurled head 23. Normally, the plug 22 effectually closes the tubular member 21 so that the upper end of the body 6 is hermetically sealed; but when the plug 22 is withdrawn, the internal threads in the tubular member 21 may serve as means for attaching 35 some ejecting instrumentality by which to discharge the contents from the container.

In the equipment of practically every person who is called upon to administer serums or the like, is one of the usual hypodermic syringes having externally threaded hubs to receive the internally threaded hubs of hypodermic needles. These interengaging threads are of standard diameter and pitch so that practically all hypodermic 45 needles will fit any syringe. To suit this condition, the tubular member 21 is provided with threads of the same standard diameter and pitch as the threads of a hypodermic syringe, thus providing that, after removing the plug 22 any hypodermic syringe 50 may be secured to the tubular member 21 the needle having previously been removed from the syringe to be used as an ejecting means for discharging the contents of the 55 container.

It is to be understood that this invention is not limited to the specific construction and organization described and shown in the drawings; on the contrary, the specific construction may be variously modified and the invention may be variously embodied, as will appear to those skilled in the art. Furthermore, it is not indispensable that all the features of the invention be used conjointly

since they may be used to advantage separately.

Claims:

1. A container for serums and the like comprising, in combination, a body portion; a stopper closing said body portion and having a passage therethrough; and a rotatable valve, to control said passage, and having an interior chamber to communicate with said passage when the valve is open; and means to connect a hypodermic needle in 75 communication with said chamber.

2. A container for serums and the like comprising, in combination, a body portion; a stopper closing one end of said body portion; and a hollow cylindrical valve plug 80 snugly fitting a socket in said stopper, said valve plug having a port passing through the wall thereof and arranged for communication with a conduit formed in said stopper and extending from the interior of the body 85 portion to the socket for the valve plug.

3. A container for serums and the like comprising, in combination, a cylindrical body portion; a stopper closing one part of said body portion; a hollow cylindrical valve 90 plug snugly fitting a socket in said stopper, said valve plug having an opening arranged for communication with a conduit formed in said stopper and extending from the interior of the body portion to the socket for 95 the valve plug; and a hypodermic needle having a shank secured to said valve plug.

4. A container for serums and the like comprising, in combination, a cylindrical body portion; a stopper closing part of said 100 body portion and having an outlet passage; a valve plug normally closing said outlet passage and having provision for opening the same; and a hypodermic needle having a shank secured to said valve plug for operating the valve.

5. A container for serums and the like having a body portion; a stopper closing part of the body portion and having an outlet passage therein; and a hypodermic 110 needle having means secured thereto and seated in the stopper normally to close said outlet passage, said means having provision for opening said outlet passage by moving the needle.

6. A container for serums and the like having a body portion; a stopper closing part of said body portion and having an outlet passage therein; and a hypodermic needle having means secured thereto and projecting 120 into the stopper normally to close said passage, said means being constructed to open said passage when turned about the axis of the needle.

7. A container for serums and the like 125 having a body portion; a stopper closing part of said body portion and having an outlet passage; and a hypodermic needle having

means secured thereto and projecting into the stopper and normally held therein frictionally to close said passage, said means being constructed to open said passage when 5 said means is moved against the frictional grip of the stopper.

In testimony whereof, I have signed my

name to this specification, in the presence of two subscribing witnesses.
